SHIELD

Laura J. Heisterberg, Sedalia, Mo.

Application July 25, 1939, Serial No. 286,455

2 Claims. (Cl. 2—174)

This invention relates to shields, and has for one of its objects the production of a simple and efficient device to be worn when a person's hair is being subjected to a stream of hot air for drying purposes, the device being so constructed and arranged as to protect the face and neck from direct contact by the hot air stream, thereby preventing discomfort to the user.

A further object of this invention is the production of a shield which is adjustable to various head sizes and is provided with a flexible apron adjacent the neck portion to permit free movement of the head of the wearer from side to side without danger of displacement of the shield caused by the striking of the shield by the shoulders of the wearer.

Other objects and advantages of the present invention will appear throughout the following specification and claims.

In the drawing:

Figure 1 is a side elevational view of the shield and drying hood, certain parts being shown in section;

Figure 2 is a top plan view of the shield;

Figure 3 is fragmentary perspective view of 25 the open end of the shield;

Figure 4 is an enlarged longitudinal sectional view taken on line 4—4 of Figure 2;

Figure 5 is a fragmentary sectional view illustrating the fastening means for the open end 30 of the shield.

By referring to the drawing, it will be seen that 10 designates the body of the shield which is preferably formed of cardboard, asbestos, or any suitable material, and constitutes a frustoconical shield which is adapted to fit around the head of a wearer, as shown in Figure 1. The inner edge of the body 10 is provided with an outwardly rolled bead 11 through which a cored or other similar means 12 is threaded, as shown.

The ends of the body 10 are adapted to be spaced, as shown in Figures 2 and 4, and one end is provided with a series of radiating perforated or scored lines 13 for producing a plurality of detachable segments 14 which segments may be removed to provide a proper fit of the shield around the head of the wearer. Each segment 14 carries a button or similar securing means 15 and the free end 16 of the cord 12 may be coiled thereabout to secure the ends of the body 10 together. The cord 12 is preferably secured in the bead 11 in a manner to prevent the accidental removal of the cord 12 from the body 10.

A fabric apron 17 is stitched or otherwise secured along one side edge to one end of the body 10, as at 18, and this apron 17 constitutes a soft overlapping means at the respective ends

of the body 10, as shown in Figure 2. The apron 17 may be gathered and folded over the free end 16 of the cord 12 as at 19, to freely slide thereover and to span the respective ends of the body 10.

The apron 17 will provide an expandable means which will be flexible in contrast to the stiff body 10 which forms the shield, and this flexible apron 17 is adapted to fit over the back of the neck in a manner to permit the wearer to easily move the head from side to side without the outer edges 20 of the shield coming into contact with the shoulders of the wearer. As stated above, the removable or detachable segments 14 will permit the shields to be placed upon the market in uniform sizes and by removing or detaching the segments 14, the sizes of the shield may be varied to comfortably fit small, medium, or large head sizes.

It should be understood that certain detail changes in the construction of the device may be employed without departing from the spirit of the invention, so long as such changes fall within the scope of the appended claims.

Having described the invention, what I claim as new is:

1. A shield of the class described comprising a stiff body having an opening for the head and separated at its respective ends to provide a slit extending from the head opening to the outer edge of the body, a retaining cord passing around the head opening, and a flexible apron spanning and closing the slit between the respective ends of the shield and adapted to lie snugly upon the back of the neck of the user and conform to the contour of the neck to protect the neck and at the same time permit the head to move freely from side to side and prevent the stiff body of the shield from scraping upon the neck.

2. A shield of the class described comprising a stiff body having an opening for the head and separated at its respective ends to provide a slit extending from the head opening to the outer edge of the body, one end of the body being provided with a plurality of detachable segments to provide a head size adjusting means, a retaining cord passing around the head opening, and a flexible apron spanning and closing the slit between the respective ends of the shield and adapted to lie snugly upon the back of the neck of the user and conform to the contour of the neck to protect the neck and at the same time permit the head to move freely from side to side and prevent the stiff body of the shield from scraping upon the neck.

LAURA J. HEISTERBERG.
